US0D1017333S

(12) **United States Design Patent** (10) **Patent No.:** **US D1,017,333 S**
(45) **Date of Patent:** **** Mar. 12, 2024**

(54) **COOLER**

(71) Applicant: **Dongguan Xinhua Xiangbao Co., Ltd.**, Guangdong (CN)

(72) Inventor: **Xinhua Huang**, Hubei (CN)

(73) Assignee: **Dongguan Xinhua Xiangbao Co., Ltd.**, Guangdong (CN)

(**) Term: **15 Years**

(21) Appl. No.: **29/898,914**

(22) Filed: **Aug. 2, 2023**

(51) LOC (14) Cl. **15-07**

(52) U.S. Cl.

USPC **D15/90; D7/605**

(58) **Field of Classification Search**

USPC D7/510, 602, 605, 608, 629; D3/202; D9/439, 443, 454, 523, 530, 535, 542, D9/544, 546, 567; D24/224, 231; D15/90; D34/2

(57) **CLAIM**

The ornamental design for a cooler, as shown and described.

DESCRIPTION

FIG. 1 is a front, right and top perspective view of a cooler, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken lines depict portions of the cooler that form no part of the claimed design.

1 Claim, 7 Drawing Sheets
